Samuel S. Bent

United States Patent Office.

SAMUEL S. BENT, OF PORT CHESTER, NEW YORK.

Design No. 3,508, dated June 1, 1869.

DESIGN FOR A NAME-PLATE.

The Schedule referred to in these Letters Patent and making part of the same.

To all whom it may concern:

Be it known that I, SAMUEL S. BENT, of Port Chester, in the county of Westchester, and State of New York, have invented or produced a new and original Design for a Name-Plate; and I do hereby declare the following to be a full, clear, and exact description of the said design, reference being had to the annexed photographic view of the same.

My present design is a modification of the design for a name-plate, patented to me October 29, 1867.

The ring *a*, upon the face of which the name is formed, and the card-receiver *b*, are ornamented with mouldings, imitation-straps *c*, and a dog, *d*, in relief, substantially as in my said former patent.

The design, of the shape and configuration of the horse *f*, with a flowing tail, forms one of the novel portions of this design.

The groundwork and ornaments below the horse form the other novel portion of this design.

The cap, *g*, gun *h*, whip *i*, flask *k*, and pouch *l*, grouped together in relief below the horse, form the ornamental configuration in the lower portion of the ring *a*.

What I claim, and desire to secure by Letters Patent, is—

The ornamental design of the shape and configuration of the name-plate, substantially as set forth.

In witness whereof, I have hereunto set my signature, this 20th day of April, 1869.

SAMUEL S. BENT.
